UNITED STATES PATENT OFFICE.

FRANK M. McDONALD, OF SEATTLE, WASHINGTON.

AERONAUTIC LANDING DEVICE.

1,342,221.

Specification of Letters Patent. Patented June 1, 1920.

Application filed December 10, 1918. Serial No. 266,047.

To all whom it may concern:

Be it known that I, FRANK M. McDONALD, a citizen of the United States, residing at Seattle, in the county of King and State of Washington, have invented certain new and useful Improvements in Aeronautic Landing Devices, of which the following is a specification.

The invention relates to means for alighting from aeroplanes, seaplanes and the like when the latter are in the air, and the object is to provide a structure, the speed of the descent of which can be varied and will strike the ground without injuring its occupants or the apparatus. Another object is to provide mechanism of this character that will float, should it land on a river or other body of water, and is provided with signaling means.

The preferred embodiment of the invention is illustrated in the accompanying drawings, wherein:—

Figure 1 is a vertical sectional view through the apparatus in its distended condition,

Fig. 2 is a detail or sectional view of the upper end of the same,

Fig. 3 is a detail view of the means for controlling the extension of the parachute member,

Fig. 4 is a horizontal sectional view illustrating in plan the hand wheel for contracting the parachute member,

Fig. 5 is a plan view of the car,

Fig. 6 is a detail sectional view on an enlarged scale of one of the feet for the car,

Fig. 7 is a detail sectional view illustrating the means for holding the parachute member in contracted condition,

Fig. 8 is a horizontal sectional view through Fig. 7,

Fig. 9 is a side elevation of the apparatus with the parachute member contracted,

Fig. 10 is a side elevation of the apparatus with the parachute member distended, and showing the apparatus when resting on the ground,

Fig. 11 is a detail plan view of the parachute outlet controlling valves.

Similar reference numerals designate corresponding parts in all the figures of the drawings.

In the embodiment disclosed, a car 23 carries a central hollow standard 2, on the upper end of which is fixed a sleeve 7. An elongated sleeve 1 is slidably and rotatably

mounted on the standard 2, below the sleeve 7. A framework, comprising elastic ribs 12 have their upper ends pivoted to a collar journaled on the sleeve 7, as illustrated in Fig. 2. This expandable and contractile frame is covered with a casing 11 of canvas or other suitable material.

The covering or casing 11 is provided with an annular series of inlet ports 13 in its lower portion and with a deflector flap 14 secured above the same to the casing 11 and flared downwardly and outwardly. The upper portion of the casing 11 is provided with a series of outlet ports 27^a, and co-acting therewith are flap valves 28. These valves 28 are in the form of disks carried by a spider, comprising an annular ring 29 and radial arms 31, the latter being fixed to the sleeve 7.

The parachute member, as above described, is adapted to be moved to its expanded condition by means of a coiled spring 29 located in the lower portion of the standard 2, and bearing against a head 28 that is engaged with the sleeve 1. The head 28 is provided with a depending knob 27 located within the standard 2 and adapted to be engaged by a pair of holding jaws 6 that embrace the same when the head is lowered. These jaws are pivoted at their lower ends, as shown at 6^a and are yieldingly urged toward each other by coiled springs 30 bearing thereagainst and having an outer abutment collar 31. Interposed between the jaws is a spreader comprising a reciprocating wedge 4 having an exposed handle knob 4^a at one end and a stop flange 4^b at its other end. The spreader is normally held in an inactive position by means of a coiled spring 4^c housed in a socket 4^b in the inner end of the spreader. One end of the spring 4^c is connected to the wedge or spreader by a pin 4^d, while its other end is connected to the standard 2 by a terminal nut or other fastener 4^e.

The operation of the apparatus as thus far described may be outlined as follows. When not in use the sleeve 1 is drawn downwardly by means of a hand wheel 3 until the head 27 is embraced and secured by the jaws 6. The parts are then in the condition shown in Fig. 9. When the device is launched, the operator has only to draw outwardly upon the handle 4^a, thus causing the wedge to spread the jaws 6 apart, releasing the head 27, the head and consequently the

sleeve 1 being then moved upwardly with respect to the standard 2 by the spring 29, causing the parachute member to expand to the form illustrated in Figs. 1 and 10. As 5 the apparatus descends it will be obvious that the flap 14 will deflect the air into the casing 11 and the discharge of said air is allowed to take place through the ports 27^a. These ports may be more or less closed by 10 turning the sleeve 1, thus moving the ports 27^a to more or less exposed positions.

The car 23 includes an annular retaining wall 24 which is preferably surmounted by an annular air chamber 15. This air chamber is in the form of a rubber tube and provides a buoyant body that will support the apparatus should it alight on water. The interior of the car is provided with an annular seat 16 beneath which are located cabinets for food, water and the like. Access 15 to these cabinets can be gained through suitable doors 18. The car is furthermore provided with landing feet 19 having yielding buffer blocks 20 on their lower ends. These 20 feet are provided with stems 21 that enter sockets in the base of the car, and are retained therein by plates 25 secured to the base by screws 26. Coiled springs 22 within the sockets, serve to yieldingly hold the feet 25 in projected relation. It will be obvious 30 that this arrangement of feet will absorb the shock in alighting.

The standard 2 carries at its upper end a signal in the form of an electric lamp 8 and 35 inclosed by a cage 9. This lamp may be supplied with current by batteries indicated at 18, said batteries being located in the car at the base of the standard 2. A suitable switch 5 on the standard and in convenient 40 relation to the occupants of the car controls the supply of current from the batteries to the lamp, as will be readily understood. The cage 9 may furthermore be surmounted by a suitable signal flag 10.

45 From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

50 Having thus fully described my invention, what I claim as new, and desire to secure by Letters Patent, is:—

55 1. In apparatus of the character described, a car, a standard extending thereabove, an 60 expandible frame mounted on the standard, a casing covering the frame and expanded to substantially globular form when the frame is expanded, means for controlling the expansion of the frame, said casing 65 having lower inlet and upper outlet ports,

and means for controlling the passage of air through the ports when the casing is in its expanded condition.

2. In apparatus of the character described, a car, a standard extending thereabout, an 70 expandible frame connected to the upper portion of the standard, a sleeve slidable on the standard and having connections with the lower portion of the frame, and a casing mounted on the frame and expanded to substantially globular form thereby when the sleeve is moved upwardly. 75

3. In apparatus of the character described, a car, a standard connected thereto, a sleeve slidable on the standard, a plurality of elastic ribs connected at their upper ends to the upper end of the standard and connected at their lower ends to the sleeve, a casing enclosing the ribs and having inlet openings 80 in its lower portion, means on the standard 85 and sleeve for holding said sleeve with the casing and ribs in contracted condition, and means for sliding the sleeve upwardly to bow the ribs and cause the casing to assume a substantially globular form. 90

4. In apparatus of the character described, a car, a hollow standard extending thereabove, a sleeve slidable on the standard, an expandible frame connected at its upper end to the upper portion of the standard and at 95 its lower end to the sleeve and surrounding the same, a casing carried by the frame, a spring within the standard and operating against the sleeve to move the same upwardly and expand the frame and casing to 100 substantially globular form, and means within the standard for holding the sleeve against movement by the spring. 100

5. In apparatus of the character described, a car, a hollow standard extending thereabove, a sleeve slidable on the standard, an 105 expandible frame connected to the upper portion of the standard and to the sleeve and surrounding the same, a casing carried by the frame, a spring within the standard and operating against the sleeve to move the same upwardly and expand the frame, jaws within the standard, a head carried by the sleeve and adapted to be engaged by the jaws, and means for operating the jaws to release the 110 head and permit the operation of the sleeve by the spring. 115

6. In apparatus of the character described, a car, a parachute member for supporting the same having an outlet port, a valve for 120 controlling the port, and means for moving the parachute member with respect to the valve to change the relation of the port to said valve.

7. In apparatus of the character described, 125 a car, a standard extending thereabove, a parachute member rotatably mounted on the standard and having an outlet port, means for rotating the parachute member, and a valve on the standard adapted to cover and 130

uncover the port on the rotation of the parachute member.

8. In apparatus of the character described, a car, a standard projecting thereabove, a sleeve rotatably mounted on the standard, an elastic frame connected to the sleeve, a casing on the elastic frame having a plurality of outlet ports, valves fixed to the standard and adapted to cover the ports, and 10 means for turning the sleeve and casing to cover and uncover the ports.

9. In apparatus of the character described, a car, a standard projecting thereabove, a sleeve slidably and rotatably mounted on the 15 standard, an expandible frame surrounding the standard and sleeve and connected to said sleeve, a casing covering the frame and having a plurality of outlet ports in its upper portion, a spider mounted on the upper 20 portion of the standard and having a plurality of valve members that rest upon the casing and are adapted to cover the ports when the sleeve is rotated, means for automatically moving the sleeve longitudinally 25 of the standard in one direction, and means

for locking said sleeve against said movement.

10. In apparatus of the character described, a car, yielding feet for the car, a standard rising from the central portion of 30 the car, a sleeve slideable and rotatable upon the standard, a plurality of elastic ribs around the standard and sleeve, said ribs being connected at their upper ends to the standard and at their lower ends to the 35 sleeve, a casing inclosing the ribs and having lower intake ports, upper outlet ports, a deflector surrounding the intake ports, a spider carried by the upper end of the standard and having valves adapted to cover the outlet 40 ports, means for holding the sleeve in its lowermost position, means for automatically elevating the sleeve on the standard when released from the holding means to expand the ribs and casing, means for turning the 45 sleeve to cause the outlet ports to be uncovered and covered by the valves, and signaling means on the upper end of the standard.

FRANK M. McDONALD.
